UNITED STATES PATENT OFFICE.

FRANK C. DENNIS, OF NEW YORK, N. Y., ASSIGNOR OF ONE-HALF TO S. M. MERRILL, OF SAME PLACE.

PARASOL.

SPECIFICATION forming part of Letters Patent No. 296,318, dated April 8, 1884.

Application filed October 29, 1883. (No model.)

To all whom it may concern:

Be it known that I, FRANK C. DENNIS, a citizen of the United States, residing at New York, in the county of New York and State 5 of New York, have invented certain new and useful Improvements in Parasols, of which the following is a specification, reference being had therein to the accompanying drawings.

Figure 1 is a central vertical section of an 10 umbrella or parasol to which my improvements have been applied. Fig. 2 is a central longitudinal section of the telescopic parasol-stem extended, and Fig. 3 a similar view, on an 15 enlarged scale, of the parasol-stem closed. Fig. 4 is a detail view of the top of the stem, showing the arrangement of the spring which holds the parasol open.

My invention relates to improvements in the 20 construction of parasols or umbrellas, and is especially adapted for use in parasols or canopies of carriages.

Heretofore, in the construction of umbrellas or canopies, they have commonly been made with a single stem or handle, and have also 25 been constructed with a sliding extension-handle, or with a stem which projected above and worked through the top of the umbrella.

My improvements consist of a stem made of 30 two or more rods or tubes arranged to slide within or telescope each other, and with a 35 spring-catch arranged on the outside and above the parasol, whereby the latter may be lowered from the top. This construction also enables the parasol to be opened without the necessity (which is usually the case with 40 parasols having short handles) of inserting the hand between the braces of the parasol.

Referring to the drawings, A represents the 45 telescopic stem of the parasol, composed of two or more sections, a, arranged to slide within each other, so as to extend or collapse. In this instance I have shown the stem made in three sections, the outer one, or the one having the greatest diameter, constituting the top part 50 of the stem, to which the collar b is attached. The bows c converge and are fastened to the collar b. The middle cylindrical section, a, serves merely as an intermediary telescopic link of the stem, and the remaining section, of the smallest diameter, carries the collar d at

its outer end, to which are attached the brace-ribs e. This collar corresponds with what is called the "runner" in an ordinary umbrella; but, instead of sliding upon the stem, it is rigidly attached to the telescopic stem and moves 55 therewith. A boss or button, f, projects below the collar d, upon which an upward pressure is exerted to raise the canopy. The inner or upper end of the lower sliding section, a, has a notch, g, or equivalent contrivance, which, 60 when the parasol is raised, takes into a lug, h, of any suitable construction, formed on a spring, i, and operated by a thumb-knob, k, which is pressed inwardly when it is desired to close the parasol. 65

Fig. 4 illustrates a sectional view of the parasol-head, showing the arrangement of spring i.

The top of the stem may or may not be provided with the usual ornamental head.

When my invention is used as a canopy for 70 carriages, it is supported by a standard, B, in the ordinary way.

The lower or smaller section, a, may be either a solid rod or a cylindrical tube.

The arrangement of the telescopic sections 75 may be reversed—that is, the largest tube, which in the drawings is shown at the top, may be arranged for operation at the bottom of the stem, and the smallest one at the top. In this case the inner end of the small rod is 80 provided with the notch g, as in the first-described arrangement, and the lower or larger tube-section provided with the knob k and spring. This reversal of the stem-sections requires no change in their construction, they 85 being simply turned end for end. By working the parasol either at the bottom or top of the stem, (the catch in both cases being outside the ribs and frame,) the parasol may be lined outside the frame, so as to entirely conceal the 90 latter from view.

I do not wish to be understood as limiting myself to the precise construction of the thumb spring-catch shown, or the notch into which it takes, for it will be obvious that a catch may 95 be constructed in various ways which will effect the same result.

The collar l, surrounding the top of the stem A, is mortised sufficiently to allow the spring i an outward movement to release the lug h 100

from the notch in the lower telescopic section. The collar then acts as a stop to limit any further outward play of the spring.

Suitable means are provided to prevent the 5 telescopic sections of the parasol-stem from coming apart. This may be accomplished in one way by pins and slots within the tube sections.

Where but two sections are used in the stem, 10 the pins or stops may be dispensed with, the bows and ribs of the parasol in that case preventing the disjointure of the stem.

Having described my invention, what I claim as new, and desire to secure by Letters Patent, 15 is—

1. An umbrella or parasol having a stem composed of two or more telescopic sections arranged to slide into each other, the upper one of which is tubular and projects above 20 the ribs or bows, substantially as described.

2. An umbrella or parasol stem composed of two or more telescopic sections, having a collar or runner rigidly attached to one of the sections, and a spring-catch arranged at the 25 top of the stem for holding the parasol when opened, substantially as described.

3. A parasol-stem composed of two or more

telescopic sections having a spring-catch for holding the umbrella open arranged at the top of the stem, whereby the catch may be operated from the outside to collapse the parasol, substantially as described. 30

4. In a parasol-stem composed of two or more sections, a spring-catch located at the top of the stem comprising the spring *i*, the 35 lug *h*, and the thumb-piece *k*, arranged diametrically opposite the spring, substantially as set forth.

5. The spring-catch consisting of spring *i*, lug *h*, and thumb-piece *k*, arranged at the top 40 of the stem, in combination with one of the telescopic sections having the notch or equivalent, substantially as described.

6. The combination of the spring *i* with collar *l*, the latter being mortised to limit the 45 play of spring when the thumb-piece is operated to close the parasol, substantially as described.

In testimony whereof I affix my signature in presence of two witnesses.

FRANK C. DENNIS.
